D. O. SNYDER

METAL RAILWAY TIE AND FASTENING

Filed Aug. 29, 1928

Inventor

D. O. Snyder,

By Clarence O'Brien
Attorney

UNITED STATES PATENT OFFICE.

DANIEL O. SNYDER, OF MUNCY, PENNSYLVANIA.

METAL RAILWAY TIE AND FASTENING.

Application filed August 29, 1928. Serial No. 302,699.

This invention relates to an improved metal railway tie especially designed to accommodate and cooperate with a special rail fastening device.

5 The invention herein disclosed is an improvement upon prior Patent No. 1,525,331, granted to me under date of February 3, 1925. Also, it is a continuation in part of Patent No. 1,688,248 granted to me under date of 10 October 16, 1928.

The novelty in the present application is predicated upon a substantially channel-shaped metal tie whose end portions are provided with longitudinally spaced openings 15 defining an intervening web, thereby permitting the base flange of the rail to rest upon this web with its edge portions overlying or projecting into the openings, and to permit the employment of a substantially C-shaped 20 clamping device.

Other features and advantages will become more readily apparent from the following description and drawings.

In the drawings:—

25 Figure 1 is a top plan view of a metal tie constructed in accordance with the present invention showing a railway rail associated with one end portion thereof, together with the retaining and clamping means.

30 Fig. 2 is a longitudinal sectional view taken approximately upon the plane of the line 2—2 of Fig. 1.

Fig. 3 is a perspective view of one of the separable clamps.

35 Fig. 4 is a perspective view of a wedge retaining plate which is associated with the clamp and base flange of the rail.

Referring now to the drawings by reference numerals, it will be seen that the reference character 32 designates a hollow steel tie of channel-shaped cross section. At each end the web portion of the tie is formed with longitudinally spaced openings 33 and 34. This arrangement provides an intervening 45 web 35 between the openings, and it is to be observed that the edges of this web are notched longitudinally to form a series of stepped shoulders 36.

The base flange of the rail R rests upon this 50 web so that the edge portions overlie or extend into the openings 33 and 34. The rail is held in place by a clamping member 37. This is of general C-shaped configuration, and it embodies a straight body portion and

right angularly disposed end portions 38 and 39 terminating in short and long hooks 40 and 41 respectively.

The clamping member occupies the position plainly shown in Fig. 2, wherein it will be observed that the body portion extends 60 underneath the web 35, thus permitting the hook 40 to be engaged simultaneously with the complementary edge of the web and adjacent side of the base flange of the rail. The hook 41 however, does not directly engage 65 the remaining portion of the base flange. Instead, a retaining wedge plate 42 is provided.

This embodies a portion 43 resting on the web and an upwardly offset portion 44 which takes over the base flange of the rail. It also 70 includes a retaining finger 45 which is bent out as shown in Fig. 1 for cooperation with the hook 41.

In cases where it becomes necessary to set the rails different distances apart it is obvious that the proper adjustment may be made through the medium of stepped shoulders 36, since the clamping member can be shifted to cooperate with the appropriate set of shoulders. In this way, an adjustable connection 75 80 between the clamping means, and web of the rail is afforded.

Having thus described my invention, what I claim as new is:—

1. In a structure of the class described, in combination, a channel-shaped metal tie having longitudinally spaced openings formed adjacent one end and providing an intervening solid web portion, a rail having its base flange resting on said web portion and projecting over into said openings, a substantially C-shaped retaining clamp having its hooked end portions extending upwardly through said openings, one of the hooks being engaged with the web and adjacent edge of the base flange of the rail, and a removable wedge retaining device driven in between the remaining hook and remaining portion of the base flange of the rail on the opposite side. 95

2. In a structure of the class described, in combination, a channel-shaped metal tie having longitudinally spaced openings formed adjacent one end and providing an intervening solid web portion, a rail having its base flange resting on said web portion and projecting over into said openings, a substantially C-shaped retaining clamp having its hooked end portions extending upwardly 100 105

through said openings, one of the hooks being engaged with the web and adjacent edge of the base flange of the rail, a removable wedge retaining device driven in between the remaining hook and remaining portion of the base flange of the rail on the opposite side, the opposite edges of said web being formed

with graduated shoulders to permit adjustable connection of the clamp therewith, and said wedge retaining plate being provided with a bendable retaining tongue portion engageable with the clamp. 10

In testimony whereof I affix my signature.
DANIEL O. SNYDER.
